APPARATUS FOR FLOWING WELLS

Herbert F. Beardmore, Oklahoma City, Okla., assignor of one-half to Indian Territory Illuminating Oil Company, Bartlesville, Okla., a corporation of New Jersey

Application July 30, 1934, Serial No. 737,621

24 Claims. (Cl. 103—231)

My invention relates to apparatus for flowing wells, particularly oil wells, with gas or air, supplied artificially in lieu of or supplement to natural gas originally accompanying the oil from the producing formation in insufficient volume to lift the oil to the top of the well, or which has been depleted to that degree, and has for its principal object to effect such artificial flow of oil from the well without interference with flow of oil from the producing formation to the well hole.

Other objects of the invention are to provide an improved apparatus for applying the artificial pressure medium, to provide application of the pressure medium at two or more stages, to provide for diverting the pressure medium from an upper stage to a lower stage, to provide a reservoir at the upper stage into which the oil is flowed from the lower stage without the hydrostatic pressure of the fluid in the reservoir acting against flow of fluid from the lower stage, and to provide for controlling application of the pressure medium in timed relation to the flow of well fluid into the reservoir.

In accomplishing these and other objects of the invention, as hereinafter pointed out, I have provided improved apparatus which is illustrated in the accompanying drawings, wherein:

Fig. 1 is a vertical perspective section through a well equipped with a flowing apparatus embodying the features of the present invention, the flowing apparatus also being shown in perspective section to better illustrate its construction and method of operation.

Fig. 2 is an enlarged section through the intermitter used in controlling flow of fluid pressure medium.

Fig. 3 is a sectional view showing the well fluid flowing into the inducer tubing from the bottom of the well.

Fig. 4 is a similar view showing the well fluid flowing from the inducer tubing to fill the reservoir from which the well fluid is blown from the well.

Fig. 5 is a similar view showing the step of blowing the well fluid from the reservoir to the top of the well.

Fig. 6 is an enlarged vertical section through the educer valve mechanism which controls discharge of the pressure medium to effect blowing of the well fluid from the reservoir and showing the diverting means whereby the pressure medium is conducted to a lower stage.

Fig. 7 is a horizontal section on the line 7—7, 55 Fig. 6.

Fig. 8 is a horizontal section on the line 8—8, Fig. 6.

Fig. 9 is a horizontal section through the injector of the first stage taken on the line 9—9, Fig. 11.

Fig. 10 is a detail perspective view of the upper end of the inducer tubing, particularly illustrating the ports through which the well fluid is flowed into the reservoir.

Fig. 11 is an enlarged vertical section through the injector comprising the first stage.

Fig. 12 is a vertical section through a well showing a modified form of well flowing apparatus.

Fig. 13 is a similar view showing a still further modified form of the invention as used in wells having sufficient formation pressure to elevate the well fluid for flow into the reservoir from which it is blown from the well by artificial pressure.

Referring more in detail to the drawings:

1 designates a well hole extending from the earth surface 2 to a subsurface oil producing stratum 3, from which oil flows into the bottom of the well hole by gravity or gas pressure. The upper portion of the well hole is provided with the usual casing 4 having its lower end seated on a cap rock formation 5 above the oil sand 3, and having its upper end projecting from the well and carrying a conventional type casing head 6 to which is connected a pipe 7 for discharging the well fluid as later described.

In some oil producing localities the pressure from the producing strata is sufficient to flow the oil through the casing and discharge it from the pipe 7. However, as the field becomes developed the natural pressure is gradually reduced until finally it ceases to flow the well and it is necessary to provide means for introducing an artificial pressure medium to take the place of the depleted gas pressure. In present practice, when artificial pressure medium is applied in a well, the pressure acts against the flow of fluid from the producing strata and reduces the production of the well below that at which the well is capable of flowing.

In practicing the present invention, I apply artificial pressure medium in such a manner that the pressure and velocity thereof promote natural flow of fluid from the producing sand rather than oppose it. I also provide for elevating the oil through a series of stages in such a manner that the hydrostatic pressure of the oil in an upper stage does not act against flow of well fluid from a preceding lower stage, as now to be described,

Referring first to the form of the invention illustrated in Figs. 1 to 11, inclusive, which show apparatus for flowing the well when the natural well pressure is depleted, suspended from the casing head 6 and extending downwardly within the casing 4 is a string of tubing 8 through which a pressure medium, such as gas or compressed air, is injected into the well for effecting flow of the well fluid, the pressure medium being supplied through a conduit 9 connected with the upper end of the tubing 8. The tubing 8 may extend into the well to within four to six hundred feet of the setting point of the casing 4 on the cap rock 5, and carries a coupling 10 for suspendingly supporting a pipe 11 connected thereto by a reduced nipple 12. The coupling 10 includes a horizontal diaphragm 13 having a central port 14 which is normally closed by a back pressure valve 15. The back pressure valve 15 has a stem 16 extending through a spider-like guide 17 on the coupling and carries a coil spring 18 having one end bearing against the guide and the other against a stop shoulder 19 on the valve stem to retain the valve in normally closed position, but which allows the flow of pressure medium through the port 14 when the pressure is sufficient to overcome the resistance of the spring 18.

The coupling 10 also carries a gas strainer 20 comprising a perforated dome-shaped member having its lower end seated about the guide 17 to prevent foreign matter that is carried with the pressure medium from clogging the back pressure valve and various air passageways and openings in the respective stages, later described.

Fixed on the pipe 11 at a point just below the swedged nipple 12 is a substantially cone-shaped skirt 21 having its lower end suspendingly supporting a string of tubing 22 of larger diameter than the pipe 11 to form an annular flow channel 23 therebetween. The tubing, however, is of substantially smaller diameter than the casing 4 to form an annular reservoir 24 that extends from the skirt 21 to a point adjacent the lower end of the casing 4 and which has its bottom formed by a packer 25. The packer 25 is secured to the string of tubing 22 as in conventional manner as close to the casing seat as is practicable and includes a compressible ring 26 sealingly engaged with the tubing 22 and inner surface of the casing 4 to prevent leakage of liquid and pressure medium from the reservoir 24 into the bottom of the well hole. The lower end of the tubing 22 extends through the packer and terminates above the bottom of the well in submergence with the well fluid flowing from the producing stratum 3.

The lower end of the tubing carries a perforated strainer 27 through which the well fluid flows into the tubing under control of a standing or check valve 28.

The standing valve 28 is of conventional design and includes a valve seat 29 adapted to be closed by a ball valve 30 adapted to move to and from engagement with the seat in guided relation within a cage 31 to allow well fluid to enter the tubing but to prevent its return when the artificial pressure medium is applied, as later described.

With the construction thus far described, the well fluid will flow into the lower end of the tubing through the standing valve until the hydrostatic pressure of the column of fluid approaches the hydrostatic pressure within the well; and in order to elevate the fluid for discharge through slotted openings 32 in the skirt 21 to fill the reservoir 24 when the natural well pressure is low

or depleted, I provide means for diverting pressure medium from the pipe 11 to an injector mechanism 33 located in the tubing 22 just above the standing valve 28.

The injector includes an inducer tubing 34 of substantially the same diameter as the tubing 11 to form an injector chamber 35. The lower end of the tubing 34 is threadedly mounted within a collar 36 that is welded or otherwise secured to the inner wall of the tubing 22 to close the annular space exteriorly of the pipe section 34 from the fluid space 37 above the standing valve 28. The upper end of the pipe section 34 terminates in spaced relation with the lower end of the pipe 11 and carries a packing element 38.

The packing element is best illustrated in Fig. 6 and includes packing rings 39 and 40 having their outer peripheries engaging the inner wall of the tubing 22 and their inner circumference engaged against the upper end of the pipe section 34. The packing rings 39 and 40 are retained between follower rings 41 and 42, the upper follower ring 41 engaging against a stop ring 43 that is welded to the wall of the pipe section 22. The lower follower ring 42 is retained in yielding engagement with the packing rings by means of a spring 44 coiled about the pipe section 34 and having its upper end bearing against the follower ring and its lower end against a seat ring 45 that is secured to the pipe section 34 by set screws 46, the set screws being threaded through the ring and engaging the pipe section.

It is thus apparent that the coiled spring 44 urges the lower follower ring into compressing relation with the packing to force it into sealing engagement with the respective inner and outer surfaces of the tubing 22 and pipe section 34 for preventing leakage therebetween.

Carried on the lower end of the pipe 11 is a diverter and educer mechanism 47 for diverting the pressure medium for flow from the pipe 11 into the annular space 48 surrounding the pipe section 34 and to allow flow of the pressure medium into the reservoir, as now to be described. The mechanism 47 is best illustrated in Fig. 6 and includes a tubular body 49 having its upper end threadedly engaged with a coupling member 50 that is secured to the lower end of the pipe 11 and has its lower end threadedly engaged with a spring seat member 51.

The coupling member 50 includes a sleeve portion 52 threadedly engaged with the pipe 11 and an externally threaded depending shank 53 threadedly engaged with the tubular body 49. Formed within the coupling member in axial alignment with the pipe 11 is a conical chamber 54 having its lower end terminating in a port 55 opening through a valve seat 56. The port 55 is normally closed by a cone-shaped valve 57 that is formed by a projecting cone-shaped lug on the upper end of a piston 58 slidable within the tubular body 49. The piston includes a skirt portion 59 having sealing means such as spaced annular grooves 60 which form liquid seals to prevent leakage around the piston. The head of the piston surrounding the conical-shaped valve 57 has a concave annular recess 61 for directing upward flow of pressure medium from the pipe 11 when the valve 57 is opened, as later described.

The piston 58 carrying the valve 57 is normally retained in the upper end of the tubular body 49 to engage and close the port 55 by means of a coil spring 62 having its upper end bearing on the bottom of the piston head and its lower end against an internal shoulder 63 formed in the

spring seat member 51. Fluid pressure is established on the bottom side of the piston through a port 64 in the spring seat member 51 to allow free movement thereof under influence of the spring 62.

When the valve 57 is closed, the fluid pressure medium is diverted through a lateral port 65 opening through the shank 53 and the tubular body 49 to connect through a nipple 66 with a by-pass conduit 67.

The conduit 67 is secured longitudinally of the side of the tubing 22 and has its lower end communicating through a port 68 with the annular space 48 surrounding the pipe section 34. Formed in the lower end of the pipe section 34 is a port 69 (Fig. 10) communicating with an injector 70.

The injector 70 comprises an L-shaped fitting having a horizontal leg 71 secured to the tubing 34 over the port 69, and a vertical leg 72 having a nozzle 73 positioned concentrically with the axis of the tubing 34 for discharging the pressure medium upwardly within the tubing to induce flow of the well fluid collecting therein upwardly through the tubing and into the annular space 23 for overflow through the slots 32 into the reservoir 24. In order to increase the injector effect of the pressure medium discharged from the nozzle 73, the tubing 34 is preferably provided with a Venturi tube 74 positioned therein directly above the leg 72 of the nozzle.

In one form of the invention, pressure medium is supplied to the pipe 9 at alternately low and high pressures, the low pressure being utilized to induce flow of well fluid into the reservoir and the higher pressure to blow the oil out of the reservoir to the top of the well as now to be described.

Connected to the pipe 9 by a Y-shaped section 15 (Fig. 1) are high and low pressure lines 16 and 17 each equipped with a shut-off valve 18 and 19 respectively, having reciprocable stems 80 and 81 connected by a common actuating lever 82.

The fulcrum 83 of the actuating lever is located intermediate the valves so that when the valve 19 in the low pressure line 17 is opened to permit flow of pressure medium under low pressure into the well, the valve 18 in the high pressure line 16 is closed and vice versa. Assuming that the pressure medium is flowing into the well from the low pressure line and the spring 62 is set to hold the piston valve 57 closed at that pressure, all of the pressure medium will be diverted through the port 65 and through the by-pass 67, then through the annular chamber 48 and port 69 to the injector nozzle 73 for discharge through the venturi 74. Velocity of the pressure medium moving through the venturi produces a pressure drop within the inlet chamber 37 so that well fluid will flow thereto through the standing valve and be moved by the jet of pressure medium upwardly through the pipe 34 and tubing 22 for overflow into the reservoir 24 through the ports 32 in the skirt 21. When the reservoir has filled, the valve 19 in the low pressure line 17 is closed and the one in the high pressure line 16 is opened to admit high pressure to the pipe 11 which acts against the area of the piston exposed through the port 55.

Acting on the bottom area of the piston at this time is the spring 62 plus the pressure of the flowing column exerted downwardly between the tubings 11 and 22 and up under the piston through the port 64; however, the pressure acting on top of the piston, namely, the pressure medium passing through the port 55 plus the head of liquid in the reservoir exerted through

ports 84 presently described and the weight of any flowing column of gas and liquid above the reservoir 24 acting on the rim 61 of the piston, preponderates over the pressures tending to hold the educer valve closed. The valve is therefore opened to pass the pressure medium from the tubing 11 to the ports 84 that lead from the piston chamber upwardly into the reservoir.

The ports 84 are formed by nipples 85 having their respective ends secured over openings 86 in the tubular body 49 and over openings 87 in the tubing 22, the openings 86 being located so that the upper edge 88 of the piston does not fully cover them, as shown in Fig. 6.

As soon as the valve opens the pressure is effective over the entire area of the piston and the piston goes down until stopped by the shoulder 89 provided by the spring seat member 51. With the ports 84 uncovered, the pressure medium will escape therethrough into the load of well fluid collected in the reservoir and on its return to the surface through the casing 4 it flows or lifts the well fluid to the surface in the form of a slug as shown in Fig. 5, the elevation of the well fluid being effected through the velocity of the pressure medium.

Upon opening of the educer valve, the velocity of the pressure fluid is at its maximum; however, the pressure tends to drop in the pipe 11 after initial escape of pressure medium through the ports 84 and consequently the velocity of return through the casing is correspondingly reduced.

Since the differential across the ports 84 determines the velocity of pressure medium through the ports and since there is a fixed relation between size of port and size of the upward flow cross-sectional area, the control of velocity across the ports also controls the velocity of flow in the flowing area.

It is well known that too slow velocity of the return causes great loss in efficiency by slippage or dropping back of the well fluid and it is, therefore, necessary to retain the pressure medium in the pipe 11 until it is of sufficient value to produce the desired differential.

This is accomplished by designing the valve so that as the pressure above the piston reduces or the pressure below the piston increases to a point that there is insufficient differential to give the proper velocity, then the spring is the over-balancing force which pushes the valve to its seat until the desired differential is reestablished.

It is thus apparent that by proper combination of port sizes and spring compression, a definite velocity range can be obtained. The valve will open and start flow with a certain velocity and when this velocity tends to fall below a certain rate, the piston automatically closes the port 55.

In extremely deep wells long lengths of tubing interfere with the delivery of large volumes of the fluid pressure medium because friction on the walls thereof reduces the effectiveness of sudden release of gas through the ports 84, but in the present invention this disadvantage is overcome by the flow educer which automatically closes when the velocity becomes too slow and remains closed until the pressure builds up in the tubing 11 and/or flowing pressure reduces in the tubing 22; however, if sufficient pressure medium is supplied through the tubing 11 the valve remains open until the entire load is discharged from the reservoir.

When the pressure drops in the tubing 11 due

to lagging of the flow of pressure medium because of friction, the spring 62 moves the piston to carry the valve to closed position and holds the valve closed until the pressure in the pipe 11 again preponderates over the pressures acting on the under side of the piston, whereupon the piston will again open to allow discharge of jets of pressure medium through the ports 84 and continue discharge of well fluid to the top of the well.

10 In order to provide an entirely automatic apparatus, it is necessary to provide means for timing the operation of the valves in the high and low pressure flow lines in timed relation with the flow of well fluid to and from the reservoir. This 15 may be accomplished by connecting the lever 82 with the actuating rod 91 of a suitable inter- 20 mittor 92. In the illustrated instance, the inter- mittor includes a diaphragm housing 93 having a chamber 94 therein divided by a flexible dia- 25 phragm 95 to form separate pressure chambers 96 and 97 on the respective sides thereof and which are alternately vented to atmosphere through ports 98 and 99 through which the rod 91 projects to connect with the diaphragm as at 30 100. The ports are controlled by valve disks 101 and 102 fixed to the rod 91 on the respective sides of the diaphragm so that when the rod is at its upper limit of travel, the valve disk 101 will close the port 98 to prevent exhaust of pressure me- 35 dium from the chamber 96 through the port. When the rod is in this position, the valve disk 102 allows exhaust of pressure medium from the chamber 97 through the port 99, the pressure medium being supplied to the chambers 96 and 97 40 at constant pressure through branch lines 103 and 104 having control valves 105 and 106 for regulating the volume of flow of pressure medium to the respective chambers.

45 In order to effect intermittent reciprocatory movement of the rod 91 whereby the valves 101 and 102 are retained in their respective positions for a definite period of time, the rod 91 carries a latch block 107 having spaced grooves 108 and 109 adapted to be alternately engaged by the 50 latch balls 110 and 111 that are carried in guides 112 and 113.

The guides 112 and 113 comprise tubes mounted in a tubular boss 114 extending upwardly from the housing 93 to form a guide for the latch block 55 107. The latch balls 110 and 111 are yieldingly retained in position to engage the respective grooves 108 and 109 by springs 115 and 116 mounted in the guides and bearing against the ball latches and against the ends of adjusting screws 117 and 118.

The branches 103 and 104 may be supplied with pressure medium through a pipe 119 connecting the respective branches with the pressure line 76, the pipe 119 being connected with the pressure line ahead of its valve 78 so that the pressure medium is continuously supplied to the branch lines 103 and 104.

The operation of the intermitter is as follows:

Assuming that the valve disk 101 is closing the 60 port 98 and the ball latches 110 and 111 are engaged with the lower groove 109 so that the rod 91 is yieldingly retained in its uppermost position holding the valve 79 closed and the valve 78 open, the fluid pressure medium flows through 65 the branch line 103 and builds up pressure within the chamber 96 until the pressure therein acting against the diaphragm 95 is such as to pre- 70 ponderate over the resistance of the ball latches 110 and 111.

75 Thereupon, the sudden release of the latch balls

will cause snap action on the diaphragm to cause the valve disk 102 to close the port 99 and the ball latches 110 and 111 to engage the upper groove 108 in the latch block 107. During this movement of the rod 91, the valve 79 is opened 5 and the valve 78 closed. The pressure medium flowing through the branch line 104 becomes effective to act against the diaphragm 95 while the pressure medium flowing through the branch 10 103 will escape to atmosphere through the port 101.

As soon as sufficient pressure builds up within the chamber 97 to overcome the resistance of the latch balls, the rod 91 will be reciprocated in the opposite direction to again effect closing of the 15 valve 79 and opening of the valve 78.

It is thus apparent that as long as pressure medium is supplied to the respective branches 103 and 104, the rod 91 will be reciprocably operated to effect alternate opening and closing of the 20 valves 78 and 79 and that the interval between separation of the valves may be regulated in timed relation with the flow of fluid to and from the reservoir 24 of the well flowing apparatus by regulating the valves 105 and 106 to control the velocity of fluid flowing through the branches 103 and 104 and thereby regulating the time required in building sufficient pressure in the respective 25 chambers 96 and 97 to overcome the resistance offered to the latch block 107.

30 In operating a flow apparatus such as illustrated in Figs. 1 to 11, inclusive, the low pressure valve 79 is opened to supply pressure medium to the well at low enough pressure that it will not be effective in opening the educer valve, 35 but the pressure medium will be diverted thereby through the by-pass 67, annular space 48, and through the port 68 to the injector nozzle 73. The velocity of the pressure medium flowing through the nozzle is directed through the venturi 74 to 40 induce flow of well fluid through the inducing chamber 35 and effect movement of fluid from the bottom of the well hole and past the standing valve 30 to replace the fluid being moved through the inducer chamber into the tubing 22 and 45 through the ports 32 at the upper end thereof into the annular reservoir 24.

The supply of pressure medium through the branch line 104 of the intermitter is regulated by adjusting its valve 106 so that the diaphragm 50 will be actuated at the time the reservoir has filled with well fluid. Upon movement of the diaphragm, the rod 91 of the intermitter is actuated to effect closing of the valve 79 in the low pressure line and opening of the valve 78 in the 55 high pressure line.

The fluid pressure medium will then flow at a higher pressure into the tubing 11. This higher pressure fluid coming into the tubing builds up pressure and acts on the area of the 60 piston exposed through the port 55.

65 This pressure aided by the pressure in the reservoir and acting on the annular rim 61 of the piston, now preponderates over the liquid, gas and spring pressures acting on the bottom of the piston to cause opening of the valve 51 so that the fluid pressure medium becomes effective over the entire area of the piston and cooperates with the hydrostatic pressure of the fluid in the casting to move the piston against the spring seat 70 member 51, whereupon jets of pressure medium are discharged through the ports 84. Since the pressure medium is now acting over the entire area of the piston, it is effective in holding the piston open so that the fluid pressure medium 75

is effective in blowing the well fluid collected in the reservoir to the top of the well. However, if the pressure in the tubing 11 tends to drop, the spring 62 then becomes effective in moving the 5 piston to closed position.

As the pressure again builds up in the tubing 11, the piston again opens to continue the flow until all of the fluid above the ports 84 has been discharged from the reservoir.

10 During operation of the educer, the hole in the bottom of the spring seat member serves as a retarder for the piston as it restricts flow of fluid to and from the piston cylinder and, therefore, retards the action of the piston and times 15 the interval at which the pressures become effective in moving the piston to and from open position.

The valve 105 controlling flow of pressure medium to the intermitter is so regulated that by 20 the time the load of well fluid has been discharged from the reservoir, the chamber 96 is filled sufficiently to effect reciprocation of the diaphragm 95 in the opposite direction to effect opening of the low pressure valve 79 and closing of the high 25 pressure valve 78, again making the injector nozzle effective in refilling the reservoir.

When the reservoir is filled, the valves are again operated to repeat the cycle of operation above described.

30 In some instances, the well may be made to flow automatically without the use of the high and low pressure lines. In such a case, the pressure medium is supplied at relatively constant pressure which is normally not sufficient to effect 35 opening of the educer. The flow of pressure medium is then diverted through the by-pass into the injector nozzle to effect filling of the reservoir by means of the injector nozzle as above described.

40 As the level of the fluid rises in the reservoir 24, the hydrostatic pressure thereof acting on the top of the piston 58 through the ports 84 becomes effective and cooperates with the pressure in the tubing 11 to open the educer valve 45 against tension of the spring 62. Immediately upon opening of the valve, the fluid pressure medium is discharged through the ports 84 to blow the load of well fluid from the well.

As soon as sufficient well fluid has been blown 50 from the well to drop the hydrostatic pressure of the fluid in the reservoir below the point where it is less than the pressure acting below the piston, the spring becomes effective to close the educer valve which again renders the injector 55 nozzle effective to refill the reservoir and the cycle is repeated as soon as the hydrostatic pressure has reached a point at which the pressure above the piston preponderates over the pressure below the piston.

60 In the form of the invention shown in Fig. 12 the injector is omitted and the injection effect is obtained in a substantially different manner. In this form of the invention the by-pass duct 67 is extended downwardly alongside the educer 65 and terminates in a concentric portion 121 having an inverted cone-shaped baffle 122 fixed to the lower end thereof, whereby the air is diverted upwardly to aerate the oil collecting in the tubing 22 above the standing valve and to cause its 70 movement therethrough for overflow into the reservoir 24. Otherwise the apparatus shown in Fig. 10 operates in substantially the same manner as that disclosed in the form of the invention above described.

75 In Fig. 13 is illustrated the apparatus as used

in a well wherein there is sufficient natural flow to raise the oil into the reservoir 24.

In this form of the invention the lower end of the pressure supply pipe 123 carries a standing valve 124 similar to the standing valve 28 5 so that when the well pressure preponderates over the pressure in the pipe 11, oil will flow through the standing valve into the pipe which acts to add to the capacity of the reservoir 126.

The valve 124 is also important as it allows the 10 reservoir to fill sufficiently through the standing valve and through the jet port 125 when the well pressure is not sufficient to lift the well fluid to the top of the tubing 22.

In this form of the invention when the pressure 15 is admitted through the tubing 11, the pressure acts to displace the fluid from the lower end of the tubing into the port 125 and force the fluid from the outer reservoir 126 to the top of the well by the jet of air escaping therethrough. 20

The tubing 11 is provided adjacent the upper end of the tubing 22 with a kick off port or drain hole 127. This port drains the tubing 11 and thereby permits the tubing to fill with liquid as above described. It also allows escape of gas 25 that may come down the tubing from leakage during a shut off period that would blow liquid out of the tubing 22.

It is also useful in aerating the liquid column 30 in the tubing 22 and reservoir. This mechanism requires an intermittent operation of the valve mechanism similar to that shown in Fig. 2 in order that the pressure medium may be turned off during filling of the reservoir and turned on when filled. 35

From the foregoing, it is apparent that I have provided an improved apparatus for flowing wells wherein the artificial pressure is prevented from interfering with flow of oil from the formation into the casing. 40

It is also apparent that due to the arrangement of the reservoirs, the hydrostatic pressure of the oil therein does not act against the upward flow of oil to the reservoir.

It is also apparent that a load may be accumulated 45 in the reservoir which will have much greater hydrostatic head than could be supported by the pressure in the formation from which the fluid was taken.

What I claim and desire to secure by Letters 50 Patent is:

1. Apparatus for flowing fluid from the bottom of a well including means at the bottom of the well for initially inducing flow of well fluid, means forming a reservoir above the bottom of the well to collect the induced flow, means for injecting a pressure medium into the well, an educer mechanism for intermittently discharging the pressure medium into the reservoir to blow the collected fluid from the reservoir, and 60 means for establishing pressure differentials on opposite sides of said educer mechanism to effect intermittent operation thereof.

2. Apparatus for flowing fluid from the bottom of a well including means for initially inducing flow of well fluid, means forming a reservoir above the bottom of the well to collect the induced flow, means for injecting a pressure medium into the well, an educer mechanism for intermittently discharging the pressure medium 65 into the reservoir to blow the collected fluid from the reservoir, and means for establishing pressure differentials on opposite sides of said educer mechanism to effect intermittent operation thereof. 70

3. Apparatus for flowing fluid from the bottom of a well including means at the bottom of the well for initially inducing flow of well fluid, means forming a reservoir above the bottom of the well to collect the induced flow, means for injecting a pressure medium into the well, an educer mechanism for discharging the pressure medium into the reservoir to blow the collected fluid from the reservoir, means for establishing pressure differentials on opposite sides of said educer mechanism to effect operation thereof, and an intermitter at the top of the well for effecting periodic injection of the pressure medium.
4. Apparatus for flowing fluid from a well including an injector at the bottom of the well, means forming a reservoir in the well at a point above the injector, means for delivering low pressure medium into the well to operate the injector to induce flow of well fluid into the reservoir, means for delivering high pressure medium into the well for blowing the fluid from the reservoir, and means alternately rendering said high and low pressure delivery means effective.
5. Apparatus for flowing fluid from a well including an injector at the bottom of the well, means forming a reservoir in the well at a point above the injector, means for delivering low pressure medium into the well to operate the injector to induce flow of well fluid into the reservoir, means for delivering high pressure medium into the well for blowing the fluid from the reservoir, means alternately rendering said high and low pressure delivery means effective, and an inducer valve in the well for diverting flow of said low pressure medium to the injector.
6. Apparatus for flowing fluid from a well including an injector at the bottom of the well, means forming a reservoir in the well at a point above the injector, means for delivering low pressure medium into the well to operate the injector to induce flow of well fluid into the reservoir, means for delivering high pressure medium into the well for blowing the fluid from the reservoir, means alternately rendering said high and low pressure delivery means effective, an inducer valve in the well for diverting flow of said low pressure medium to the injector and releasing the high pressure medium to the reservoir.
7. A well flowing apparatus including a casing extending to a point near the bottom of the well, a tubing in the casing, means connected with the tubing and cooperating with the casing to form an open top reservoir in the casing, means connected with the upper end of the tubing for delivering a pressure medium to the tubing, an injector carried below the tubing, means for diverting the pressure medium from the tubing to the injector for inducing flow of well fluid into the reservoir, and an educer connected with the tubing and operable in response to hydrostatic head of fluid in the reservoir for delivering the pressure medium to the reservoir for elevating the well fluid collecting therein.
8. A well flowing apparatus including a casing extending to a point near the bottom of the well, a tubing in the casing, means connected with the tubing and cooperating with the casing to form an open top reservoir in the casing, means connected with the upper end of the tubing for delivering a pressure medium to the tubing, means for inducing flow of well fluid into the reservoir, and an educer connected with the tubing and operable in response to hydrostatic head of fluid in the reservoir for delivering the pressure medium to the reservoir for elevating the well fluid collecting therein.
9. A well flowing apparatus including a casing extending to a point near the bottom of the well, a tubing in the casing, a tubing depending from the lower end of the first named tubing and having its upper end in communication with the casing, a packer on the depending tubing and engaging the casing to form a reservoir in the lower end of the casing for collecting well fluid delivered through the depending tubing, a standing valve on the lower end of the depending tubing, an injector in the depending tubing for inducing flow of fluid therethrough into the reservoir, a by-pass connecting the injector with the first named tubing, and an educer fixed to the lower end of the first named tubing for delivering pressure medium into the reservoir and for diverting pressure medium through said by-pass to the injector.
10. A well flowing apparatus including a casing extending to a point near the bottom of the well, a tubing in the casing, a tubing depending from the lower end of the first named tubing and having its upper end in communication with the casing, a packer in the depending tubing and engaging the casing to form a reservoir in the lower end of the casing for collecting well fluid delivered through the depending tubing, a standing valve on the lower end of the depending tubing, an injector in the depending tubing for inducing flow of fluid therethrough into the reservoir, a by-pass connecting the injector with the first named tubing, and a pressure actuated educer fixed to the lower end of the first named tubing for delivering pressure medium into the reservoir and for diverting substantially all of said pressure medium through said by-pass to the injector incidental to a definite reduction in pressure of said pressure medium.
11. In combination with a well casing, a well flowing apparatus including a tubing suspended in the casing for injecting an artificial pressure medium into the well, a larger tubing suspended from the first named tubing cooperating with the casing to form a reservoir for collecting a body of well fluid and having a port communicating directly with the reservoir, an educer casing carried by the tubing and having a valve seat above said port, a valve engaging said seat for controlling flow of pressure medium from the tubing through said port, a piston having one end connected with said valve and having said end subject to the hydrostatic head of well fluid in the reservoir acting through said port and tending to unseat said valve and means normally supporting the piston with the valve in closed position and yieldable in response to said pressure medium supplemented by the hydrostatic head of well fluid to allow discharge of the pressure medium through said port.
12. Apparatus for flowing fluid from a well including an injector at the bottom of the well, means forming a reservoir in the well at a point above the injector, means for delivering pressure medium into the well to operate the injector to induce flow of well fluid into the reservoir, and control means for said pressure medium actuated responsive to hydrostatic head of fluid in the reservoir supplemented by said pressure medium for admitting said pressure medium into said reservoir to elevate the fluid from the reservoir.
13. A well flowing apparatus including a casing extending to a point near the bottom of the well, a tubing in the casing, an apertured skirt on the

- tubing, a second tubing suspended from the skirt and cooperating with the casing to form an open top annular reservoir in the casing, means connected with the upper end of the tubing for delivering a pressure medium to the tubing, an injector, means supporting the injector from the tubing, means for diverting the pressure medium to the injector for inducing flow of well fluid through the last named tubing and through the aperture of said skirt into the reservoir, and an educer connected with the first named tubing for delivering the pressure medium to the reservoir for elevating the well fluid collecting therein.
14. Apparatus for flowing fluid from a well including means for introducing a low pressure medium into the lower portion of the well to effect an initial flow of well fluid, a reservoir in the well for receiving said initial flow, means for delivering a high pressure medium into the well for inducing flow of fluid from the reservoir, and means alternately rendering said high and low pressure mediums effective.
15. Apparatus for flowing wells including means for introducing a pressure medium into the well for inducing flow of well fluid from the bottom of the well, means located in the well at a point above the bottom of the well for collecting the induced flow, means for intermittently releasing the pressure medium for elevating the collected induced flow, and means controlling duration of said intervals responsive to pressure differentials in the well at the point of collection.
16. Apparatus for flowing fluid from a well having sufficient formation pressure to flow the fluid into the well, a reservoir in the well for receiving well fluid at substantially the normal liquid level in the well, means for supplying a pressure medium to the well, an educer for intermittently admitting pressure medium into the reservoir for blowing the collected fluid from the reservoir, means for establishing pressure differentials on opposite sides of the educer to effect intermittent operation thereof responsive to accumulations of pressure medium above the educer, and an intermitter at the outlet of the well for effecting periodic injection of the pressure medium.
17. Well flowing apparatus including in combination with well casing and tubing for conducting an artificial pressure medium into the well, means cooperative with the well casing to form an open top reservoir for collecting a body of well fluid and having ports, an educer casing carried by the tubing and having a valve seat and ports below said valve seat connected with the ports in said cooperating means and having a vent port, a valve for said seat, a piston connected with said valve, having its upper and lower ends subjected to the hydrostatic head of fluid in the well and in the reservoir through said connected ports and through said vent port respectively, and a spring in the educer casing normally retaining the valve closed and yieldable upon preponderance of pressure on said valve and on the upper end of the piston to release said pressure medium into the reservoir for elevating the well fluid.
18. Well flowing apparatus including a reservoir communicating with the outlet of a well, a collecting chamber communicating with the well inlet and with the reservoir, a fluid pressure medium supply line, an inducer in constant communication with the supply line for inducing fluid from the well inlet to the collecting chamber, means including a valve resistant to pressure of fluid in the supply line providing controlled
- supply of fluid pressure medium from the line to the reservoir, and means for supplying fluid pressure medium to the supply line under alternately high and low pressure.
19. Well flowing apparatus including a reservoir communicating with the outlet of a well, a collecting chamber communicating with the well inlet and with the reservoir, a fluid pressure medium supply line, an inducer in constant communication with the supply line for inducing fluid from the well inlet to the collecting chamber, means including a spring urged valve responsive to differential in pressure of fluid medium in the line and the spring and to differential influence of hydrostatic head of fluid on opposite sides of the valve providing controlled supply of pressure medium from the line to the reservoir.
20. Apparatus for flowing fluid from a well having sufficient formation pressure to flow the fluid into the well, means in the well for effecting elevational flow to establish a hydrostatic head in the well greater than can be normally supported by said formation pressure, a reservoir for collecting the elevational flow adjacent the level of said head, means for injecting a pressure medium into the well, an educer for intermittently discharging the pressure medium into the reservoir to flow the collected fluid from the reservoir, and means for establishing pressure differentials on opposite sides of said educer to effect intermittent operation thereof.
21. Apparatus for flowing fluid from a well having sufficient formation pressure to flow the fluid into the well, means in the well for effecting elevational flow to establish hydrostatic head in the well greater than can be normally supported by said formation pressure, a reservoir in the well for collecting said elevational flow adjacent the level of said head, means supplying a pressure medium to the well, an educer for intermittently discharging the pressure medium into the reservoir to flow the collected fluid from the reservoir, means for establishing pressure differentials on opposite sides of the educer to effect intermittent operation thereof responsive to accumulations of pressure medium above the educer, and an intermitter at the outlet of the well for effecting periodic injection of the pressure medium.
22. Apparatus for flowing fluid from a well having a sufficient formation pressure to flow the fluid into the well, means for introducing a low pressure medium into the well for inducing an elevational flow to establish a hydrostatic head greater than can be normally supported by said formation pressure, collection means in the well for collecting the elevational flow adjacent the level of said head, and means for introducing a high pressure medium into the fluid in said collection means for inducing flow of the collected fluid toward the top of the well.
23. Apparatus for flowing fluid from a well having sufficient formation pressure to flow the fluid into the well, means for introducing a low pressure medium into the well for inducing elevational flow to establish a hydrostatic head greater than can be normally supported by said formation pressure, collection means in the well for collecting the fluid adjacent the level of said head, means for introducing a high pressure medium into the fluid in said collection means to induce flow of the collected fluid toward the top of the well, and means rendering said high pressure medium effective for inducing flow of the collected fluid.
24. In a well flowing apparatus including a tub-

ing for injecting an artificial pressure medium into a well, means cooperating with the tubing to form a reservoir for collecting a body of well fluid and having ports, an educer casing carried by the 5 tubing and having a valve seat above said ports, a piston slideable in the casing, a valve connected with the piston for engaging said seat for controlling flow of pressure medium from the tubing through said ports, a spring normally supporting

the piston with the valve in closed position and yieldable in response to said pressure medium to allow discharge of the pressure medium, and bypass means connected with said tubing above the valve seat and discharging into the well below the educer casing for diverting all of said pressure medium to induce flow of well fluid into the reservoir when the valve is closed by said spring. 5

HERBERT F. BEARDMORE.
